UNITED STATES PATENT OFFICE

JOSEPH H. ALLEN, OF CHICAGO, ILLINOIS, ASSIGNOR TO INLAND GLASS WORKS, INC.,
OF CHICAGO, ILLINOIS, A CORPORATION OF ILLINOIS

LAMP SHADE

Application filed November 9, 1931. Serial No. 573,841.

This invention relates to lamp shades and particularly lamp shades or globes used for street lighting purposes. More specifically the invention relates to lamp shades, preferably in the form of globes of the type disclosed and claimed in my copending application Serial No. 563,957, filed September 21, 1931.

The primary object of the invention is to provide a novel lamp shade of generally globular design which is provided with a relatively rectangular or multi-sided portion for the reception of a continuous flexible street name carrying band or strip.

Another object is to provide a translucent lamp globe of relatively globular shape having a multi-sided portion formed about a part of the globe, which portion is translucent, behind which a resilient translucent name carrying band or strip is arranged, whereby the entire appearance of the globe with its cooperating band will have the appearance, coloring and characteristics of a single unitary and uniform article, both when lighted from the outside, as in daylight, or when lighted from the inside, as at night.

A further object of the invention is to provide a lamp globe for street lights and other purposes which has a multiple sided channel for the reception of a name carrying band, the walls of the side channels being slightly bowed and connected at their ends with a rounded integral portion to provide a continuous surface behind which a resilient continuous name carrying band is positioned.

Numerous other objects and advantages will be apparent throughout the progress of the following specification.

The accompanying drawing illustrates a selected embodiment of the invention and the views therein are as follows:

Fig. 1 is a detail longitudinal sectional view of the improved lamp globe.

Fig. 2 is a detail cross sectional view on the line 2-2 of Fig. 1.

Fig. 3 is a detail perspective view of one type of name carrying band or strip.

Fig. 4 is a detail perspective view of the strip shown in Fig. 3, the strip being flexed or doubled to permit it to be readily insert-

ed in the relatively small opening provided in the globe.

Fig. 5 is a detail perspective view of a modified form of insignia carrying member.

Fig. 6 is another modification of the name carrying band.

Fig. 7 is a detail sectional view on the line 7-7 of Fig. 6.

Fig. 8 is a detail sectional view of a form of band in which the supporting band is continuous.

The shade or globe 6 may be molded out of glass and comprises an upper globular portion 7, a lower supporting connecting flange or neck 8, and a multi-sided intermediate portion or part 9. The multi-sided portion or part 9 is integrally connected to the globe 7 and the neck 8, as indicated at 10 and 11 respectively. The connecting portion 10 is so arranged that rays from the lamp arranged inside of the globe will not be intercepted and cast a shadow on the multi-sided portion 9. This multi-sided portion 9 extends a predetermined distance beyond the lower outer edge of the globe and the neck to provide a channel-shaped chamber 13 extending peripherally about the globe above the neck and on the inside of the globe, for the purpose of receiving a band or strip 14 which is supported on the inwardly extending supporting ledge 15. Street name insignia 16 may be painted on the exterior surface of the band 14, the insignia being a different color than the band, so that the insignia may be read from the outside of the globe.

The entire globe 6, with the exception of the peripheral portion 9, is preferably treated as by frosting, spraying, or otherwise in order to provide substantially non-glaring, light diffusing characteristics, while the peripheral portion 9 is left clear and sufficiently translucent as indicated at 17, so that the insignia or characters 16 on the band 14 may be easily seen and read through the transparent portion 17.

It should be understood that when I use the term "globe" or "globular", I do not necessarily mean a lamp shade of spherical form but any shell-like lamp shade is included by the terms.

The clear transparent part 9 comprises a plurality of sides 18 which are slightly bowed outwardly, as clearly shown in Fig. 2. The bowed sides 18 are integrally connected at 5 their ends and rounded, as indicated at 19, the portions 19 preferably being formed of a radius of one inch. The bowed sides 18 and the rounded connecting corners 19 provide a smooth continuous channel or surface into 10 which the band 14 is arranged.

The band or strip 14 is made of flexible materials such as celluloid, which is sanded or otherwise rendered translucent, as indicated at 20 so that, when the band is inserted in 15 the chamber 13, the translucent band will be seen through the transparent portion 17 of the globe, thus giving the appearance that the entire globe, including the multi-sided peripheral portion 9, is translucent. The 20 transparency of the walls or sides 18 permits the characters or insignia 16 on the band to give the globe the appearance, coloring and characteristics of a single unitary and uniform article, both when lit from the outside, 25 as in daylight, and when lit from the inside as at night.

The side walls 18, as well as being bowed outwardly, are inclined downwardly, as clearly shown in Fig. 1. The band or strip 14, 30 which may be made from a single strip of material having its free ends connected together, as indicated at 21, to form a continuous band, may be tapered, as clearly shown in Fig. 3, to make it conform with the inclined or tapering side walls of the peripheral portion 9. Due to the resilient characteristics of the band, the band will tend to hug the inner surfaces of the side walls 18 and connecting portions 19 to bow the outer 35 face of the band and bring the characters tight against the walls, permitting the characters to be legibly and clearly seen or read through the transparent walls 18. The inclination or tapering formation of the walls 40 18, and the inclination or tapering formation of the band or strip 14, cause the band to drop downwardly by gravity and thus tighten itself in position in the chamber 13, there normally being a slight space 22 left 45 between the bottom edge of the band and the ledge 15. However, when the band is in position in the globe for a certain period of time, the band will set and tend to conform with the shape of the peripheral portion and 50 later rest upon and be supported by the ledge 15. The band 14 is thus held in tight contacting relationship with the transparent peripheral portion 9, which portion includes the sides 18. Due to the normal expandable 55 characteristics of the band, the band will tend to expand and hug the walls and drop downwardly by gravity, thereby tightening itself in position.

In Figs. 5 to 8, inclusive, modified forms 60 of bands are shown. The band shown in

Fig. 5 comprises a plurality of name carrying members 23 which are fastened at their corners to connecting clips 24. The members 23 may be made of relatively rigid material, while the connecting members 24 may be made of relatively flexible material, thus permitting the band to attain its resilient characteristics.

In Figs. 6 and 7 a flexible resilient wire 25 may be made continuous and the members 23 may be carried by this wire in any particular manner, such as indicated at 26.

Another way of making the band is by forming a complete peripheral band 27 and attaching this band to a flexible flat metal tape 28. The metal tape 28, therefore, tends to expand the band 27 and press it outwardly against the walls 18 of the globe.

A globe constructed in accordance with the invention is highly efficient and presents a pleasing appearance; the translucent globe, having a transparent portion behind which a band is arranged of the same tint as the body of the globe, presents the appearance of having the street name or other insignia 85 painted directly on either the inner or outer surface of the globe itself. In employing the present arrangement it will not be apparent that the strip is separate and removable.

The construction herein shown and described provides a lamp globe having street signs which are relatively parallel with the streets whose names are designated. The tapering sides permit the street name to be read at the proper angle and the bowing of the sides permits the strip to expand into position without wrinkling, overlapping, or bulging. The street names are thus legible, and, whenever it is desired to change the names of the street, a new name carrying band may be inserted in place. The band is arranged inside of the globe and thus protected from the elements.

Changes may be made in the form, construction, and arrangement of the parts without departing from the spirit of the invention or sacrificing any of its advantages, and the right is hereby reserved to make all such changes as fairly fall within the scope of the following claims.

I do not herein claim the broad subject-matter relating to the mounting of sign-carrying means within lamp shades as set forth in my co-pending application Serial Number 512,857, filed February 2, 1931; nor the subject-matter of invention relating broadly to the mounting of the edges of the sign cards in a groove as set forth in my co-pending application, Serial Number 526,944, filed April 1, 1931; nor do I claim herein the subject-matter of invention relating broadly to the mounting of a continuous name band within a lamp shade as set forth in my co- 125

pending application Serial Number 563,957, filed September 21, 1931.

The invention is hereby claimed as follows:

- 5 1. A lamp shade having a transparent portion, the transparent portion being multi-sided, a name carrying member arranged behind the transparent portion of the globe, and means arranged inside of the globe for holding said member. 70
- 10 2. A lamp shade having an integral multi-sided portion, and a name carrying band arranged inside of the shade and behind the multi-sided portion. 75
- 15 3. A lamp shade having an integral multi-sided transparent portion, and a name carrying band arranged inside of the shade and behind the multi-sided portion. 80
- 20 4. A lamp shade having an integral multi-sided portion, and a resilient name carrying band arranged inside of said shade, and means for supporting said band in position inside of the shade behind the multi-sided portion. 85
- 25 5. A lamp shade comprising a translucent wall portion having a distinct coloring and an adjacent transparent multi-sided portion, an insignia carrying member arranged inside of said multi-sided portion, said member being translucent and of a desired comparative coloring with respect to the translucent portion of the shade. 90
- 30 6. A lamp globe comprising a translucent globular portion and a transparent multi-sided portion, said multi-sided portion having side walls bowing outwardly horizontally and inclining vertically and adapted to receive an insignia carrying member there behind. 95
- 35 40 7. A lamp globe comprising a translucent globular portion and a transparent multi-sided portion, said multi-sided portion having side walls bowing outwardly, the juncture of the adjacent side walls comprising curved portions and adapted to receive an insignia carrying member therebehind. 100
- 45 8. A lamp shade comprising a translucent portion and a transparent multi-sided portion, said multi-sided portion having side walls bowing outwardly and tapering downwardly. 105
- 50 9. A lamp shade comprising a translucent portion and a transparent multi-sided portion, said multi-sided portion having side walls bowing outwardly, and a resilient name carrying member arranged inside of said shade in a position to be seen through the translucent side walls of said shade. 110
- 55 10. A lamp shade comprising a translucent portion and a transparent multi-sided portion, said multi-sided portion having side walls bowing outwardly, the juncture of the adjacent side walls being rounded, and a continuous resilient member arranged inside of said shade and conforming with the shape 115
- 60 of the multi-sided portion and insignia carried by said member and adapted to be seen through the side walls. 120
- 65 11. A lamp shade comprising a translucent portion and a transparent multi-sided portion, said multi-sided portion having side walls bowing outwardly, the juncture of the adjacent side walls being rounded, said side walls also tapering downwardly, and a member arranged inside of said shade, said member having resilient characteristics so that it will expand inside of the shade and hug the inside walls of the multi-sided portion of the walls. 125
- 70 12. A lamp shade comprising a translucent portion and a transparent multi-sided portion, said multi-sided portion having side walls bowing outwardly, the juncture of the adjacent side walls being rounded, said side walls also tapering downwardly, a member arranged inside of said shade, said member having resilient characteristics so that it will expand inside of the shade and hug the inside walls of the multi-sided portion of the walls, said member being tapered to conform with the side walls of said shade and insignia carried by said member and adapted to be seen through said side walls. 130
- 75 13. A lamp shade comprising a translucent portion and a transparent multi-sided portion, said multi-sided portion having side walls bowing outwardly, the juncture of the adjacent side walls being rounded, said side walls also tapering downwardly, a member arranged inside of said shade, said member having resilient characteristics so that it will expand inside of the shade and hug the inside walls of the multi-sided portion of the walls, said member being tapered to conform with the side walls of said shade and insignia carried by said member and adapted to be seen through said side walls. 135
- 80 14. A lamp shade comprising a lower portion having angularly disposed side walls of transparent material, a translucent shade extending upwardly from the lower portion, insignia carrying means arranged inside of the shade behind the transparent portion, and means formed in the inside of the shade contiguous to the lower portion for supporting the insignia carrying means. 140
- 85 15. A lamp shade comprising a lower portion having angularly disposed side walls of transparent material, a translucent shade extending upwardly from the lower portion, said lower portion having an opening therein, insignia carrying means arranged inside of the shade behind the transparent portion, said insignia carrying means being greater in length than the circumference of said opening, and means formed in the inside of the shade contiguous to the lower portion for supporting the insignia carrying means. 145

16. Information display means for lamp mounting on a lamp shade in position there-
in such that each of the several insignia groups will be displayed in the lamp shade
facing different angular directions, said band being normally substantially flattened
throughout each portion containing an insignia group, and each substantially flattened
portion having a slight outward curvature. 70
16. Information display means for lamp shades comprising a continuous band pro-
vided with insignia means arranged therein in spaced apart groups, said band being
adapted for mounting on a lamp shade in position therein such that each of the several
insignia groups will be displayed in the lamp shade facing different angular directions,
said band being normally substantially flattened throughout each portion containing an
insignia group. 75
17. Information display means for lamp shades comprising a continuous band pro-
vided with insignia means arranged therein in spaced apart groups, said band being
adapted for mounting on a lamp shade in position therein such that each of the several
insignia groups will be displayed in the lamp shade facing different angular directions,
said band being normally substantially flattened throughout each portion containing an
insignia group, and each substantially flattened portion having a slight outward curva-
ture. 80
18. A lamp shade comprising a translucent wall portion and an adjacent transparent multi-sided portion, an insignia-carrying member mounted inside the lamp shade behind said multi-sided portion, said member comprising a band of translucence substantially similar to that of the translucent wall portion of the shade. 85
19. A lamp shade comprising a translucent wall portion and an adjacent transparent multi-sided portion, an insignia-carrying member mounted inside the lamp shade behind said multi-sided portion, the translucent portion of said lamp shade being frosted and the member, comprising a translucent strip 90
40 of material, having a white color characteristic and a translucence substantially the same as that of the frosted portion of the lamp shade whereby when the member is mounted behind the transparent portion of
45 the shade the entire shade will have the appearance of being uniformly frosted both in the translucent and transparent portions. 95
20. Information display means for lamp shades comprising a continuous band pro-
vided with insignia means arranged therein in spaced apart groups, said band being formed to present the insignia groups in relatively tilted position and adapted for mounting on a lamp shade in position therein such
50 that each of the several insignia groups will be displayed in the lamp shade facing different angular directions, said band being normally substantially flattened throughout each portion containing an insignia group. 100
21. Information display means for lamp shades comprising a continuous band pro-
vided with insignia means arranged therein in spaced apart groups, said band being formed to present the insignia groups in relatively tilted position and adapted for
55 60 65 110 115 120 125 130

In witness whereof, I have hereunto sub-
scribed my name.

JOSEPH H. ALLEN.
